UNITED STATES PATENT OFFICE

2,570,555

SUPPORTING DEVICE FOR DROPCLOTHS

Anthony Hudoba, Struthers, Ohio

Application March 29, 1949, Serial No. 84,100

2 Claims. (Cl. 211—86)

1

This invention relates to supporting devices and more particularly to a supporting device attachable to a ladder and serving to hold a drop cloth beneath an area to be painted.

The principal object of the invention is the provision of a support device for drop cloths.

A further object of the invention is the provision of a lightweight, inexpensive support device for drop cloths.

A still further object of the invention is the provision of a support device for drop cloths providing a relatively large supporting area, the size and shape of which may be varied as desired.

The support device for drop cloths disclosed herein comprises a simple and inexpensive rectangular bracket adapted to be secured to a leg of a stepladder or other ladder in any desired position with respect to the side, back or front thereof and to carry a plurality of lightweight rods over which a drop cloth may be positioned to protect a floor or wall area from paint accidentally dropped as in carrying out a painting operation thereabove.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a side view of a stepladder showing the drop cloth supporting device secured thereto.

Figure 2 is a perspective view of the drop cloth supporting device with parts broken away.

By referring to the drawings and Figure 1 in particular it will be seen that a stepladder including front legs 10 having steps 11 secured therebetween is shown in open position supporting a drop cloth supporting device 12 thereon. The drop cloth supporting device (as may best be seen by referring to Figure 2 of the drawings) comprises a generally rectangular body member having a plurality of openings 13 in oppositely disposed relation in its sides and a plurality of oppositely disposed openings may be formed in its end sections, if desired.

The rectangular body member of the support device 12 is preferably formed of a section of strip material bent in the form of a U, the ends

of which are indicated by the numerals 15 and 16, respectively. The open end of the U is closed by an extension 16A formed in a circle and doubled back upon the section side of the support

device 12, the portion of the extension 16A registering with the side of the support device 12 being indicated by the numeral 16B. A transverse member 24 with bent ends 25 and 26 is positioned between the sides of the rectangular body

12 and connected thereto as by welding or brazing. The transverse member 24 is spaced inwardly with respect to the ends of the rectangular body member 12 and may be provided with openings 14 in oppositely disposed relation to the openings 13 in the end section of the device if desired. Openings 17—17 are formed in the side of the support device 12 and in the end 16B and a bolt and nut assembly 18 positioned therethrough so that a clamping action may be imparted to the circular portion of the extension 16A as about a paint can, shown in dotted lines and indicated by the numeral 19.

Two pairs of oppositely disposed openings 20 and 21, respectively, are positioned between a portion of the extension 16A and the opposite side of the rectangular body member 12 and adjacent the end 15 thereof and a pair of bolt and nut assemblies 22—22 are positioned therethrough so that the device may be clamped about the leg 10 of the stepladder as shown in Figure 1 of the drawings. The leg is positioned between the bolts 22—22 and the end 15 and the extension 16A, respectively. It will be seen that the tightening of the bolts 22—22 will support the device on the stepladder when the nuts thereon are tightened.

A plurality of rods 23 are positioned transversely of the device through the openings 13—13 so that a drop cloth may be positioned over the relatively wide area of the device and thereby provide protection against the dropping of paint or other material on the area covered.

It will be obvious to those skilled in the art that the device may be secured to either side of any one of the legs of the stepladder shown in Figure 1 or on the front, back or sides of any other ladder and that the rods 23 may be of any desired length so that any given areas may be covered.

It will also be seen that the device provides a simple and convenient support means for a paint can and thereby provides a combination particularly desirable and useful in connection with interior decorating.

It will thus be seen that the several objects of

the invention are met by the supporting device for drop cloths disclosed herein.

Having thus described my invention, what I claim is:

1. A drop cloth support comprising a rectangular body member having a pair of parallel spaced extensions formed on one end thereof for engagement about a supporting object and means positioned between the extensions for urging the same together so as to secure the device to the said supporting object, the said rectangular body member having a plurality of oppositely disposed openings therein and a plurality of rods removably positioned in said openings to form a drop cloth supporting platform.

2. A drop cloth support comprising a rectangular body member having a pair of spaced parallel extensions formed on one end thereof for engagement about a supporting object, the other end having several openings therein, means positioned between the extensions for urging the same together so as to secure the device to the said supporting object, the sides of the said rectangular body member having a plurality of oppositely dis-

posed openings and a plurality of rods removably positioned in said openings to form a drop cloth supporting platform, a transverse member spanning said rectangular body midway between its ends and having openings therein in longitudinal alignment with the said openings in the said other end so that the said removable rods may be positioned in the device crossways.

ANTHONY HODOBA.
